UNITED STATES PATENT OFFICE.

ALBERT L. DUFF AND JAMES W. MATHESON, OF BROOKLYN, NEW YORK.

WARDROBE TRUNK.

Application filed June 25, 1920. Serial No. 391,630.

To all whom it may concern:

Be it known that we, ALBERT L. DUFF and JAMES W. MATHESON, citizens of the United States, and residents of the city of New York, borough of Brooklyn, in the county of Kings and State of New York, have invented a new and Improved Wardrobe Trunk, of which the following is a description.

10 Our invention relates to wardrobe trunks and has for its general object to provide a trunk of the indicated class having novel means for hanging garments in the wardrobe section of the trunk in a manner that

15 hung garments may be compact in the trunk or slid out of the trunk and disposed in any one of various angular positions to be readily accessible.

The nature of the invention, its distinguishing features and advantages will clearly appear as the description proceeds.

Reference is to be had to the accompanying drawings forming a part of this specification, it being understood that the drawings are merely illustrative of one example of the invention.

Figure 1 is a perspective view of a wardrobe trunk embodying our invention showing the same in open position and with the 30 garment-hanging means in inner position in the wardrobe section of the trunk;

Figure 2 is a sectional plan view of the trunk in the closed position, the section being taken just below the top of the trunk;

35 Figure 3 is a fragmentary sectional plan view on an enlarged scale at the right of the wardrobe section of the trunk;

Figure 4 is a vertical section on the line 6—6, Figure 2;

40 Figure 5 is a longitudinal vertical section on the line 7—7, Figure 4;

Figure 6 is a view similar to Figure 5, showing a modified carriage for the garment supporting arms, the trunk parts 45 shown in Figure 5 being omitted;

In the illustrated example the numeral 15 designates generally the drawer section of our improved trunk, and 16, the wardrobe section, said sections having a suitable 50 hinge connection as indicated at 17.

In the wardrobe section 16 of the trunk our improved garment-hanging means is provided and includes upper and lower parallel fixed tracks 32 suitably supported 55 as by upper and lower members 33, rigid

with the front of a bracket plate 34, suitably fastened to the inner wall of the wardrobe section 16. A track section 35 is of U-shape to present upper and lower tracks corresponding with the fixed tracks 32 and 60 pivotally secured to the latter as at 36, whereby said U-shaped hinged track section may be swung to an inner position within the wardrobe section 16 as in Figures 1, 4 and 6, or swung out of said wardrobe section as 65 shown in Figure 5. A carrier 37 is adapted to slidably engage the fixed track section 32 or the swingable track section 35 and may be slid from the fixed tracks to the swingable ones when the respective tracks 70 are in alinement. Said carrier has suitable means for engaging the tracks. In the form shown in Figure 7 the upper and lower ends 38 are rounded to engage above and beneath the respective tracks, there being an 75 additional curved member 39 above the lower track to prevent detachment of the carrier from the tracks. In the form shown in Figure 6 the carrier 37^a has the lower member 38 as well as a member 39 to engage the lower track rail 32 or the corresponding track rail on the swingable section 35. At its upper end 37^b the carrier 37^a is bent inwardly and downwardly or twice at right angles, so that it accommodates and forms bearings for the axles of 85 grooved wheels 37^c to run on the top track rails.

On the carrier 37 or 37^a hanger bars 40 are provided with hooks 41 or equivalent means on which garment hangers A may be suspended. The bars 40 are preferably arranged in pairs, the bars of a pair being provided with a suitable clamp conventionally indicated at 42 for clamping 90 trousers legs. The free ends of the hanger bars 40 when in position within the trunk are afforded support on a ledge 43 preferably in the form of an angle bar. Also, preferably the bars 40 of a pair are swingably connected with the carrier, there being shown for the purpose strap-hinge elements 46 on said bars secured by hinge pins 45 passing through the same and through upper and lower lugs 44 on the carrier 37 105 or 37^a. From the foregoing it will be readily apparent that the carrier with the series of hanger bars may be slid onto the tracks 32 to be housed within the wardrobe section 16. Or, the swingable track section 35 110

may be swung outward into alignment with the fixed tracks, thereby permitting the carrier to be slid onto said swingable track section, and whereby said swingable track section and said carrier with its hanger arms may be positioned at various angles clear of the trunk section 16.

In wardrobe trunks of the type to which our invention relates, the hanger arms are 10 swingably mounted on what is termed a backboard, said backboard being fixedly secured to the trunk at the interior. In our invention the carrier 37 constitutes a slideable backboard as distinguished from a 15 fixed backboard and it carries the garment hangers mounted thereon to be slideable therewith on the respective track sections.

As will readily be understood, the carrier 37, when the track rails 32, 35 are in 20 alignment, may be slid partly on to the fixed rail 32 and partly on to the swingable section 35, in which position of the parts it will be clear that the carrier forms a lock between the fixed and pivoted rails to maintain them in alignment and prevent the 25 supported hangers from swinging or vibrating about the axis of the hinge 36. Thus the hanging and removal of the garments will be attained by less annoyance by 30 the swingable track rails being held rigid.

It is to be noted moreover that the rails 32, 35 constitute a means whereby the carrier 37, with the clothes hangers thereon, can be given a sliding movement into or 35 out of the trunk, and this is in addition to the capability of swinging the hangers and carrier into and out of the trunk about the axis of the hinge 36.

We would state in conclusion that while 40 the illustrated example constitutes a practical embodiment of our invention, we do not limit ourselves strictly to the mechanical details herein illustrated since manifestly the same can be considerably varied without departure from the spirit of the invention as defined in the appended claims.

Having thus described our invention, we claim:

1. In a wardrobe trunk, a fixed track 50 section, a pivoted track section swingable to a position within the trunk or to an outer position alining with the fixed section, a garment-hanging backboard slideable to or from either of said track sections when the same 55 are alined, and a series of elongated garment-hanging arms mounted on said backboard to slide therewith on the track sections, said arms projecting at approximately right angles to the face of the backboard and being laterally swingable on the

backboard into an approximately parallel relation or in spread form.

2. In a wardrobe trunk, a fixed track-section, a carrier constituting a backboard, garment-hanging means on said backboard, said backboard being accommodated on said track section and being slideable thereon, and an auxiliary track section pivotally supported at one end on the trunk adjacent to the outer end of the fixed track section, and swingable 65 approximately in a horizontal plane to a position in the trunk or to a position outside the trunk and movable when outside the trunk either in alinement with the fixed track section or to different angular positions at either side of the fixed track section, said backboard when the track sections are 70 alined being slideable to or from either track section.

3. In a wardrobe trunk, upper and lower 80 fixed track sections, a pivoted track section presenting upper and lower tracks, corresponding with the fixed track sections and swingable laterally to aline therewith or to positions within the trunk or outside of the 85 latter, a carrier constituting a backboard and adapted to slidably engage either of said track sections, and garment-hanging means mounted on said slideable backboard and slideable therewith on said track sections. 90

4. In a wardrobe trunk, a fixed track section within the trunk, a second track section pivoted at one end adjacent to the outer end of the fixed section to swing horizontally into the trunk or out of the same, and a 95 backboard slideable from either track section to the other, said swingable track section when disposed outside of the trunk being movable on its pivot into alinement with the fixed section, or to various angular positions 100 at either side of the fixed section to thus variously dispose the backboard in positions at either side of the fixed track section, and garment supporting means on said backboard.

5. In a wardrobe trunk, a fixed track section within the trunk, a second track section at the front of the trunk and pivotally mounted at one end, said pivoted track section adapted to be swung in a horizontal plane to various angular positions outside of the trunk, and a carriage affording accommodation for garment hangers thereon, said carriage movable from either track section onto the other track section and swingable laterally with the outer track section 110 when moved onto the latter. 115
